His Attorney.

UNITED STATES PATENT OFFICE.

FRANK A. BYLES, OF SCHENECTADY, NEW YORK, ASSIGNOR TO GENERAL ELECTRIC COMPANY, A CORPORATION OF NEW YORK.

ELECTRIC REGULATOR.

Application filed June 17, 1926. Serial No. 116,762.

My invention relates to electric regulators and more particularly to current regulators of the vibratory type for use in electrical systems in which a constant current is desired. The invention finds particular application in the motion picture industry where arc lamps, and especially direct current arc lamps, are used as the source of screen illumination. As is well known, it is particularly desirable to maintain constant current in the arc lamp circuit, since a small change in current causes a material change in the illumination on the screen. Many motion picture houses find it desirable to provide two projection machines so arranged that the second machine may be operated simultaneously with a machine in operation for a short period of time in order to change from one reel of film to another without delay. This necessitates operating two arc lamps either in parallel or in series. Arrangements in which the two lamps are operated in parallel during the change-over have the disadvantage of overloading the generator, if a motor generator set is used, and the newly started arc has a tendency to draw an unequal share of current during the initial period of adjustment. Hence, it has been found desirable to operate the arc lamps in series during the change-over.

If two projector arc lamps are to be operated simultaneously in series, the source of supply must be capable of furnishing a constant current over a wide range of voltage in order to operate successfully a single arc or a plurality of series connected arcs. The well known series arc generator, designed with a drooping voltage-current characteristic, approximates some of the characteristics desired, but does not in itself secure constancy of current in the arc lamp circuit. Even if this drooping characteristic is exaggerated and the usual type of current regulator is used, the result obtained is only an approximately constant current. The results heretofore obtained may be sufficiently accurate for general illumination purposes but where a more rigorous current regulation is demanded, as in motion picture projectors, an absolute constancy of illumination is desired. It has been found that the known regulators are not sufficiently sensitive or rapid in operation to accomplish entirely satisfactory results.

It, therefore, is an object of my invention

to provide an improved current regulator capable of operating with a generator having a wide voltage range, which is sensitive and sufficiently rapid in operation to maintain a substantially constant current in a series arc circuit during any operating condition imposed when arcs are used alternately or when a single or a plurality of arcs are operated continuously.

The novel features which I believe to be characteristic of my invention are set forth with particularity in the appended claims. The invention itself, however, both as to organization and method of operation, together with further objects and advantages thereof, will be better understood by reference to the following description taken in connection with the accompanying drawing in which Fig. 1 is a diagrammatic illustration of a system in which my invention has been embodied, and Fig. 2 is an explanatory diagram showing a suitable voltage current characteristic for the supply generator.

In Fig. 1 a dynamo-electric machine 1 is shown diagrammatically as a direct current generator and may be driven in any convenient manner, as, for example, by an alternating current motor (not shown) connected to commercial supply mains. This dynamo-electric machine is adapted to operate with a drooping voltage-current characteristic, such as is indicated in Fig. 2, and, as shown, is provided with a shunt field winding 2 and a series field winding 3. The generator is wound for a high open circuit voltage and the series winding is connected to oppose the shunt winding so that the machine will supply an approximately constant current over the desired working range. A rheostat 4 is provided in the circuit of the shunt field winding 2 and the effectiveness thereof is controlled by the current regulator to be described presently. Arc lamps 5 and 6 provided with suitable electrodes, are shown diagrammatically in a series circuit with the generator 1 and are provided respectively with shortcircuiting switches 7 and 8, which provide a means for putting any desired lamp or lamps into operation.

As shown in the drawing, a regulator 9 is arranged to control the shunt field excitation of generator 1 so as to maintain the current constant in the arc lamp circuit. Regulator 9 comprises cooperating contacts 10 and 11, a core 12, and windings 13, 14 and 15.

The contact 11 is arranged to be stationary and is screw-threaded to provide a means for adjusting the contact gap so that the regulator may be arranged to hold different current values. The contact 10 is arranged to be movable and is resiliently mounted in order to permit a higher contact speed than is possible with a moving contact mechanism having appreciable inertia. Contact 10, as shown, is supported by means of a spring 16 formed of a light, thin, flat ribbon of steel, rigidly attached at its ends to a fixed support 17 which is secured to the core 12. Adjacent the contact 10, and approximately at the middle of the supporting spring 16, is secured a magnetic armature 18, which is arranged to cooperate with the core 12 and its operating windings 13, 14 and 15. Winding 13 is connected in series relation with the load circuit and is of low resistance and commonly constructed of a few turns of relatively large wire. With normal changes in current, the action of winding 13 would be entirely too sluggish to effect the rapid correction desired. To provide a rapid vibratory movement of contact 10, winding 14 is connected in series with a resistor 19 across the shunt field winding 2 and is arranged to act accumulatively with winding 13. The action of this winding, however, has a tendency to cause the regulator to hold a lower current, as the operating voltage of the generator increases. To compensate for this tendency, I provide a winding 15 arranged to act differentially with respect to windings 13 and 14. Winding 15 is arranged to be responsive to the voltage impressed upon the load circuit and is connected in series with a resistor 20 across the terminals of generator 1.

The cooperating contacts 10 and 11 are arranged to actuate a relay 21, which is provided to periodically shortcircuit or insert the resistance 4 in the circuit of field winding 2. Relay 21 comprises an operating coil 22 and contacts 23 which are connected in a parallel circuit to resistance 4. A condenser 24 is connected across contacts 23 in order to prevent excessive sparking. The operating coil 22 is arranged to be responsive to the voltage impressed upon the load circuit and is connected in series with a resistor 25 across the terminals of generator 1. The main control contacts 10 and 11 of regulator 9 are so connected as to shortcircuit the relay magnet winding 22 when they close. This sequence of operation means that the relay contacts and main control contacts will open and close together when in operation.

Similarly to the conditions existent with the usual type of vibratory regulator, the resistance 4 is of such a magnitude that it has considerable effect on the voltage of generator 1 and, when included in a circuit with the shunt field winding 2, reduces the voltage of the generator considerably below the de-

sired value and, when removed therefrom, allows said voltage to increase considerably above the desired value. If, therefore, the contacts 10 and 11 be rapidly opened and closed, the contacts 23 will be opened and closed and the voltage of the generator will be repeatedly varied and its value will depend upon the relative length of the periods during which the contacts are opened and closed. The length of these periods will depend upon the distance by which the fixed and moving contacts are separated at each vibration, and this distance will be determined by the attracting flux in the core 12.

Let it be assumed that the dynamo-electric machine is in operation with the electrodes of the respective arc lamps 5 and 6 separated. For purposes of explanation, let it be assumed that the dynamo-electric machine 1 is designed to have an open circuit voltage of say, 180 volts, which drops to approximately 60 volts, when one lamp is burning and automatically increases its voltage to approximately 120 volts, when the second arc is struck. Assume, now, that shortcircuiting switch 8 is closed and that arc lamp 5 has been put into operation and is burning with an impressed voltage of approximately 60 volts and a current of approximately 80 amperes flowing in the circuit. This point of operation may, for convenience, be considered to be at point A on the voltage-ampere characteristic shown in Fig. 2. Now assume that the arc conditions change and that regulator 9 has been adjusted to hold 80 amperes.

If contacts 10 and 11 are in the position shown, contacts 23 will be open and the voltage impressed upon the field winding 2 will be a minimum. The winding 14 of the regulator 9 will, at this instant, have a minimum energization, and, hence, the spring 16 will move contacts 10 and 11 into engagement. Upon the engagement of contacts 10 and 11, the winding 22 of relay 21 is shortcircuited so that contacts 23 will be closed to shortcircuit the resistance 4, and the voltage impressed upon the field winding 2 will thereupon increase to a maximum. Upon an increase in the voltage across the shunt field winding 2, the energization of winding 14 will increase, whereupon the contacts 10 and 11 will be disengaged. Contacts 23 will again be opened so that the voltage impressed upon field winding 2 is reduced to a minimum. This cycle of operation is rapidly repeated and the contact 10 is rapidly vibrated by the operating winding 14. If the current in the load circuit varies, the energization of the current winding 13 will be changed to vary the mean position of the vibrating contact 10 so that the voltage of generator 1 will be varied to maintain substantially constant current in the load circuit.

If the load circuit resistance increases, it will be necessary to increase the generator

voltage in order to maintain the current constant. This means that contacts 10 and 11 must remain in engagement more of the time. However, with an increase in voltage, the 5 voltage impressed across the operating winding 14 will tend to maintain contacts 10 and 11 out of engagement for a longer period of time, and this would tend to cause a lower voltage to be generated, and hence a lower 10 current to be held than would correspondingly be held at lower voltages. In order to compensate for this effect, winding 15 is arranged to operate differentially with respect to winding 14. Since winding 15 is energized 15 in response to the terminal voltage of generator 1, it will tend to maintain contacts 10 and 11 in engagement for a longer period of time as the voltage increases, and hence will counteract the tendency of winding 14 to regulate 20 for a lower current as the voltage increases.

Now, if it is desirable to start the second lamp 6, its electrodes are brought together and the shortcircuiting switch 8 is opened. This permits the current through the first 25 lamp to flow through the tips of the electrodes of the second lamp. The arc is then struck and the two lamps are now operating in series and may, for convenience of explanation, be considered as operating at the point 30 B on the voltage-ampere characteristic shown in Fig. 2. The operation of the regulator under these conditions will be evident from the description previously given in connection with the operation of one lamp, since 35 the current in the load circuit is still maintained at the same value and coils 14 and 15 are subjected to an increase in voltage of the same proportion.

If it is now desired to change over from 40 one lamp to the other, the electrodes of the first lamp are brought together and the short-circuiting switch closed so that the projection may be continued with the second lamp.

While I have shown and described a particular embodiment of my invention and a 45 particularly useful application thereof, it

will be apparent to those skilled in the art that the invention may be applied in other relations of utility and changes and modifications may be made without departing from 50 my invention, and I, therefore, aim in the appended claims to cover all such changes and modifications as fall within the true spirit and scope of my invention.

What I claim as new and desire to secure 55 by Letters Patent of the United States, is,—

1. In combination with a generator having a field winding and a load circuit and adapted to operate with a drooping voltage-current characteristic, of a regulator for maintaining constant current in said load circuit comprising a winding responsive to the current in said load circuit, a winding responsive to the voltage of said field winding and arranged to operate accumulatively with respect to said current winding, a vibrating contact comprising a resiliently supported contact member actuated by said windings, and a winding responsive to the voltage of 60 said generator and arranged to operate differentially with respect to said first-mentioned windings.

2. In a system of distribution, a plurality of arc lamps arranged for operation singly or in series, a generator having a field winding and adapted to supply substantially constant current to said arc lamps, a regulator for regulating the current in said field winding for maintaining constant current through said arc lamps comprising a winding responsive to the current through said lamps, a winding responsive to the voltage of said field winding, a vibrating contact comprising a resiliently supported contact member actuated by said windings, and a winding responsive to the voltage of said generator for modifying the action of said vibrating contact throughout the voltage range of said generator.

In witness whereof, I have hereunto set 90 my hand this 16th day of June, 1926.

FRANK A. BYLES.
